UNITED STATES PATENT OFFICE.

LOUIS H. BECKER, OF SEYMORE, INDIANA.

FIRELESS HOVER.

1,106,768.

Specification of Letters Patent. Patented Aug. 11, 1914.

Application filed January 2, 1913. Serial No. 739,731.

To all whom it may concern:

Be it known that I, LOUIS H. BECKER, a citizen of the United States, residing at Seymour, in the county of Jackson and State of Indiana, have invented new and useful Improvements in Fireless Hovers, of which the following is a specification.

This invention relates to brooders and more particularly to a specially constructed fireless hover.

The primary object of the invention is to provide a device of this character particularly adapted for use in poultry yards where motherless chickens or other fowls are hatched by means of an incubator, as the device is constructed in such a novel and peculiar manner as to provide warmth and a cover for all motherless chickens without the use of fire for such warming purposes.

Another object of the invention is to provide a knock-down hover capable of being quickly taken apart for cleaning purposes and again re-assembled without in any way affecting the utility thereof, and to further provide a device which is not only durable and simple in construction but reliable and efficient in operation and one which can be manufactured and placed upon the market at a minimum cost.

The above and additional objects are accomplished by such means as are illustrated in their preferred embodiment in the accompanying drawings, described in the following specification and then more particularly pointed out in the claims which are appended hereto and form a part of this application.

In describing my invention in detail, reference will be had to the accompanying drawings wherein like characters denote like or corresponding parts throughout the several views, and in which:

Figure 1 is an elevation of the device complete. Fig. 2 is a longitudinal vertical sectional view. Fig. 3 is an elevation of the housing showing the door thereof partly open. Fig. 4 is a plan view of the supporting ring and its accessories, and Fig. 5 is an enlarged fragmentary view.

Referring now more particularly to the drawings, wherein is illustrated the preferred form of my invention, the numeral 1 designates the outer wall or body portion of my device, which is preferably circular and provided with a plurality of screened open-

ings 2 by means of which light and air are admitted to the interior of the hover. To brace or strengthen the wall 1 the top and base thereof is bent as at 3, the base portion adapted to rest upon the ground, as there is no bottom to the device.

A cover 4 preferably cone-shaped and having an air vent 4', is provided for the purpose of protecting the interior of the hover, and has formed integral therewith a flange 5 of substantially the same size and shape as the body portion 1 so as to fit thereupon. Before placing the cover 4 upon the body portion 1, a sheet of woolen or other soft material 6 is interposed therebetween to prevent the entrance of cold air and dampness into the interior of the hover. The outer edge of this sheet is slit as at 7 to form tongues 8 which depend upon all sides of the hover to materially add to the appearance of the device and to offer a greater amount of resistance against the dislodgment of said sheet, as well as to present a soft outer surface to the wall.

Upon the interior of the wall and near the top thereof is secured a plurality of brackets 9 adapted to support a ring 10, which in turn supports a plurality of uniformly spaced apart transversely extending rods 11 terminating at each end in eyes 12 through which the ring passes, the said rods being so arranged as to provide in substance a suitable grating. A cloth strip 13 is passed over each rod 11 and depends from the sides thereof. The said strips loosely depending from the rods 11 will offer a soft, warm cover somewhat similar to that of the mother hen, thus it will be seen that chickens within the hover are as thoroughly and fully protected from the elements as though beneath their mother. An opening 14 is formed upon one side of the body portion to permit access to the interior of the hover, which opening may be closed when desired through the medium of a door 15 slidably mounted within guides 16 upon the outer face of the device.

From the foregoing, taken in connection with the accompanying drawings, it will be seen that a device constructed in accordance with my invention is capable of housing and protecting small chickens against rain, cold and other injurious weather conditions; that new strips may be substituted as desired without destroying or affecting the effi-

ciency of the device; and that the whole device may be taken apart and re-assembled at will or as occasion demands.

It is thought from the foregoing that the 5 advantages and novel features of my invention will be readily comprehended.

I desire it to be understood that I may make slight changes in the construction and in the arrangement and combination of the 10 several parts, provided such changes fall within the scope of the subjoined claims.

Having thus described my invention what I claim as new and desire to secure by Letters Patent is:—

15 1. A device of the character described including a body portion, a removable cover therefor, a sheet of soft material interposed between said cover and said body, the said cover serving as a securing means therefor, 20 a plurality of tongues arranged to loosely depend exteriorly of the said body, the said tongues being formed by slitting the said material, the said tongues forming a cover for openings of the said body, a ring within 25 said body, a plurality of uniformly spaced apart transversely extending rods carried by said ring, and a slit strip of soft material carried by each of said rods, said slit portion of the said strip adapted to depend between 30 the said rods to a point adjacent the floor of the hover, as and for the purpose set forth.

2. A device of the character described including a body portion, a removable cover therefor, soft material interposed between 35 said cover and said body portion, a plurality of tongues arranged to loosely depend exteriorly of the said body, the said tongues being formed by slitting the said material, certain of the tongues forming a cover for 40 openings of the said body, a ring within said body, a plurality of rods carried by said ring, and a slit strip of material carried by each rod, the said slit portion of each strip adapted to depend between the said rods to 45 a point adjacent the floor of the hover, as and for the purpose set forth.

3. A device of the character described including a body portion having a plurality of screened openings formed therein, a removable cover having an opening formed therein, a sheet of soft material interposed between said cover and said body portion, the cover serving as a securing means therefor, a plurality of tongues arranged to loosely 50 depend exteriorly of the said body, the said tongues being formed by slitting the said

material, a door mounted for sliding movement upon the outer face of the said body portion adjacent one of the said body openings, the said door adapted to open and close 60 communication between the interior and exterior of the said body, the said door and the other screened openings being normally covered by certain of the depending tongues, a ring within said body a plurality of uniformly spaced apart transversely extending rods carried by said ring, and a slit strip of soft material carried by each of said rods, the said slit portion of the said strip adapted to depend between the said rods to a point 70 adjacent the floor of the hover, as and for the purpose set forth.

4. A device of the character described comprising a substantially cylindrical body portion having a plurality of screened openings formed therein, a removable cover having an opening formed therein, a sheet of soft material interposed between the said cover and said body portion, the cover serving as a securing means therefor, the said 80 material adapted to overlap the edges of the said body portion and depend exteriorly thereof, a plurality of tongues arranged to loosely depend exteriorly of the said body, the said tongues being formed by 85 slitting the extended portion of the material, a door mounted for sliding movement upon the outer face of the said body portion adjacent one of the said body openings, the said door adapted to open and 90 close communication between the interior and exterior of the said body, the said door and the other of the said openings being normally closed by certain of the said tongues depending thereover, a ring carried 95 by and within the said body portion near the top thereof, a plurality of rigidly supported brackets upon which the said ring is supported, a plurality of uniformly spaced apart transversely extending rods carried by 100 the said ring, and a strip of soft material carried by each of the said rods, each strip being slit at intervals throughout its entire length to provide depending portions which are suspended from the said rods and extend 105 to a point adjacent the base of the hover, as and for the purpose set forth.

LOUIS H. BECKER.
